UNITED STATES PATENT OFFICE.

HENRY C. EGERTON, OF PASSAIC, NEW JERSEY, ASSIGNOR TO WESTERN ELECTRIC COMPANY, INCORPORATED, OF NEW YORK, N. Y., A CORPORATION OF NEW YORK.

TELEPHONE APPARATUS.

1,365,898.

Specification of Letters Patent. Patented Jan. 18, 1921.

Application filed January 8, 1918. Serial No. 210,850.

To all whom it may concern:

Be it known that I, HENRY CLIFFORD EGERTON, a citizen of the United States, residing at 63 Bond street, Passaic, in the county of Passaic and State of New Jersey, have invented certain new and useful Improvements in Telephone Apparatus, of which the following is a full, clear, concise, and exact description.

10 This invention relates to telephonic apparatus, and more especially to magnetic structures for use in such apparatus, being particularly suitable to loud speaking telephone receivers.

15 An object of this invention is the production of a highly efficient magnet system for telephonic apparatus, which is compact, rigid and of firm parts, readily assembled and adjusted.

20 In accordance with this invention a magnet is provided with pole pieces with which are associated rigid members secured to the pole pieces, and by which, when the air gap between the pole pieces has once been determined, the pole pieces are held in corresponding spaced relation to maintain this definite air gap. These pole pieces and members form an inclosure within which a translating coil may be mounted.

25 Other objects and features of the invention will be apparent from the following description.

This invention is illustrated in several embodiments in the accompanying drawings, 35 wherein—

Figure 1 shows in perspective a loud speaking receiver containing a magnet system embodying features of this invention; Fig. 2 is an exploded view of the pole piece 40 and coil arrangement shown in Fig. 1; Fig. 3 shows a vertical cross-section of the receiver of Fig. 1 taken on the line 3—3 thereof; and Figs. 4 and 5 show modifications of the pole piece mounting of Fig. 1.

45 In the construction shown in Fig. 1, the magnetic structure comprises a permanent magnet 6, to opposite ends of which magnetic pole pieces 7 and 8 are respectively secured. Each pole piece is provided with a 50 pair of pole extensions 9, 9 which are separated to receive a pair of translating coils 10, 10 therebetween. Spacing pins 11 are

provided to aid in holding the coils in place, and to provide a space in which resilient torsion members 12, 12, carrying an armature 13 of magnetic material firmly secured to these members, may move without touching the coils. The pole piece 7 is secured to the upper side of the magnet 6 and the pole piece 8 to the lower side thereof, so as to bring the pole extensions 9, 9 of one pole piece opposite the pole extensions 9, 9 of the other pole piece. The coils 10 are located on opposite sides of the members 12 with the respective ends 14 and 15 of the armature 13 extending through the open centers of the coils, the centers being made of such size that movement of the armature during operation of the receiver is not interfered with. The ends of the armature 13 extend between the respective pairs of pole extensions 9, 9 of the pole pieces 7 and 8, and the end 15 carries a rod 16 secured to a vibratory diaphragm 17, as shown in Fig. 3.

In order that efficient and uniform operation be obtained in apparatus of this character, it is of great importance that a construction be provided in which the pole pieces can be adjusted to secure the most desirable air-gap relation and rigidly maintained in this position. The present construction provides for relative longitudinal, transverse and vertical adjustment of the pole pieces, so that slight inequalities in the various parts are easily compensated for in adjustment. To accomplish this purpose L-shaped members 18 of rigid non-magnetic material are provided. Each of these members 18 is secured to its companion pole piece by a screw 19 passing through an opening 20 in such pole piece, and engaging a threaded recess 21 in such member. The openings 20 are preferably counterbored to receive the head of the screw 19, and both the opening and counterbore are larger than the shank of the screw 90 and the head, respectively, so that the members 18 can be adjusted both longitudinally and transversely relative to their companion pole piece. The members 18 are also provided with grooves 22 designed to receive 95 screws 23, for which threaded recesses 24 are provided in the respective opposing pole pieces. The grooves 22 are slightly wider and deeper than the threaded portion of the

screws 23, to provide for both vertical and transverse adjustment of the screws therein. Sleeves 25 are carried by the screws 23, to space the members 18 a definite distance 5 from their respective opposing pole piece, the members 18 providing sufficient bearing for the sleeves 25 and the heads of the screws 23, so that after these parts are properly adjusted, they will be rigidly held against 10 accidental movements.

In order to explain the method by which the pole pieces are adjusted relative to each other, assume that the pole extensions 9 of the pole pieces 7 and 8 are separated too 15 far vertically, and are also out of both longitudinal and transverse alinement. The screws 34 and 36 are first loosened and then with the members 18 held tightly in position on their companion pole pieces, the 20 latter are moved vertically to obtain the proper air gap between them; whereupon the screws 23 are tightened. The transverse alinement of the pole pieces can also be obtained either wholly or in part in this step 25 of the adjusting operation through the engagement of the screws 23 with the members 18.

If still further adjustment is necessary to obtain proper transverse alinement, either one or both of the screws 19 may then be 30 loosened, and the pole pieces moved into proper transverse position. The screws 19 may then be tightened again to retain this adjustment and after proper positioning of the nut 39, should this be necessary to compensate for the change in vertical adjustment, the screws 34 and 36 will next be tightened, thus completing the adjusting operation. It will be noted that each of the 35 pole pieces is mechanically secured to the other by the two members 18 and the screws and sleeves coating therewith to provide a structure wherein each of the parts so braces the others as to retain the parts in adjustment, even though the apparatus be 40 subjected to severe jar or vibration. A rectilinear housing is also formed through this construction of a size to hold the coils in place; the pins 11 serving to space the coils apart to prevent their interfering with the 45 movement of the members 12-12.

The mounting of the armature 13 is such that it can be independently adjusted without disturbing the relative adjustment of the pole pieces 7 and 8. This is accomplished by providing an opening 26 in each 50 of the members 12, which are slightly longer and wider than the threaded portion of a screw 27, adapted to pass therethrough for engagement with a threaded recess 28 in its 55 respective member 18. A delicate transverse and vertical adjustment of the armature 13 is thereby provided and aids in producing a very sensitive and efficient receiver.

The pole extensions 9-9 of each of the 60 pole pieces are of the same polarity as the

ends of the magnet 6, to which their respective pole pieces are attached, and as the armature 13 depends on the passage of telephonic currents through the coils 10 for magnetization, the pole extensions 9-9 of the 70 opposing pole pieces normally exercise a balancing attraction on the armature. The coils 10 have the same direction of winding and surround the opposite ends 14 and 15 of the armature. These coils are preferably 75 connected in series, and are designed to be included in the telephonic receiving circuit. The passage of fluctuating voice currents therethrough induces magnetic flux in the armature, which changes in direction and 80 strength in accordance with the voice currents developing a corresponding variance in the attraction and repulsion of the armature 13, relative to the pole extensions 9-9, to move the armature correspondingly 85 against the torsion of the members 12-12. The armature movements are imparted to the diaphragm 17, which is thus set in vibration and produces sounds corresponding to the telephonic currents traversing the 90 coils 10.

The electromagnetic structure and the diaphragm may be mounted in any suitable manner, and are shown as supported upon a front plate 30, preferably of non-magnetic 95 material, having a recess 31 at the rear thereof to receive the diaphragm 17 which is retained therein between annular washers 32-32, preferably of yielding material. A metallic retaining ring 33, preferably of 100 non-magnetic material, is secured to the rear surface of the front plate 30 to hold the diaphragm in place. The magnetic structure is secured to the plate 30 by screws 34, 35 and 36, extending through suitable openings 105 in the magnet 6 and ring 33, to engage threaded recesses in the plate 30. The screws 34 and 36 are preferably of magnetic material and also extend through openings 37 and 38 in the respective pole 110 pieces 8 and 7, and thus also serve to secure these pole pieces to the magnet 6. The screw 34 clamps the pole piece 8 firmly between the magnet 6 and ring 33, whereas the screws 35 and 36 are each provided with lock nuts 39 and 40; the former serving to hold the magnet 6 against movement relative to these screws, and the latter serving to lock the screws in place after adjustment 115 to space the magnet 6 the desired distance from the plate 33.

The front plate 30 has an extension 41 with a sound opening 42 therethrough, the extension being designed to support a suitable horn (not shown). In practice a suitable casing (not shown) would be secured to the front plate 30, to inclose the working parts of the receiver and protect them against exposure. Binding posts 43 are carried by the front plate for connection to 120 125 130

an exterior telephonic circuit, and conductors 44, connecting the binding posts with the coils 10, would serve to convey the actuating telephonic currents to these coils to operate the receiver.

The modification shown in Fig. 4 differs from the construction shown in Figs. 1 to 3 inclusive, in that the pole piece 8' has an upwardly extending flange 45 tapped to receive a screw 46 to secure this pole piece to the magnet 6'. The magnet has the end 47 thereof shaped, as shown, to provide a proper bearing for the pole piece, and the opening 48 therein for the screw 46 is somewhat larger than the threaded portion of the screw to provide for a limited longitudinal and transverse adjustment of the pole piece 8', relative to the pole piece 7 as well as relative to the end 47 of the magnet. The construction is otherwise substantially the same as shown in Fig. 1.

Fig. 5 shows in full lines a pair of members 49, which may be used in place of the members 18 and sleeves 25, shown in Fig. 1; the angular extensions 50 on the members 49 taking the places of the spacing sleeves 25. The pole pieces 7 and 8 are shown in dotted lines to indicate their position relative to the members 49.

What is claimed is:

1. In telephonic apparatus, a magnet, a pair of pole pieces carried by said magnet and adjustable to vary the air gap therebetween, a pair of rigid members extending between said pole pieces, and means coöperating with said pole pieces and rigid members to adjust the air gap between said pole pieces and to rigidly maintain the adjusted position therebetween.

2. In telephonic apparatus, a magnet, a pair of pole pieces carried by said magnet arranged in overlapping parallel spaced relation to each other and adjustable to vary the overlapping relation therebetween, a pair of rigid members extending perpendicularly to overlapping portions of each of said pole pieces to maintain the spaced relation therebetween, and means coöperating with said pole pieces and rigid members to adjust the overlapping relation between said pole pieces and to rigidly maintain the adjusted position therebetween.

3. In telephonic apparatus, a magnet, a pair of pole pieces carried by said magnet arranged in overlapping parallel spaced relation to each other and adjustable to vary both the air gap and the overlapping relation therebetween, a pair of rigid members extending between said pole pieces, and means coöperating with said pole pieces and rigid members to adjust both the air gap and overlapping relation between said pole pieces and to rigidly maintain the adjusted position therebetween.

4. A magnetic structure comprising a

magnet having its opposing poles oppositely directed in overlapping relation, and means interposed between said overlapping poles to maintain a spaced relation between such poles.

70

5. A magnetic structure comprising a magnet, pole pieces attached thereto and projecting beyond the ends of said magnet in oppositely directed overlapping relation, and means interposed between the projecting end of one pole piece and the other pole piece to position said pole pieces relative to each other.

75

6. A magnetic structure comprising a magnet having its ends adjacent, pole pieces for said magnet ends each extending toward the opposite end of the magnet and beyond the other pole piece, and means interposed between the pole pieces to position said pole pieces relative to each other.

80

7. A magnetic structure comprising a magnet having its ends adjacent, angular pole pieces for said magnet ends each extending beyond the opposite pole piece in alignment with the magnet and angularly toward the opposite pole piece, and means interposed between the pole pieces to position said pole pieces relative to each other.

90

8. A magnetic structure comprising a magnet having a pole piece at each end, said pole pieces being attached at one end to their respective ends of the magnet and having their other ends free and arranged in spaced overlying relation to each other, and a pair of rigid members, one having one end thereof rigidly secured to the free end of one pole piece and the other end having one end thereof rigidly secured to one end of the other pole piece, the other end of the one member being rigidly secured to the other pole piece, and the other end of the other member being rigidly secured to the one pole piece, to maintain the spaced relation between said pole pieces.

95

9. A magnetic structure comprising a magnet having a pole piece at each end, said pole pieces being attached at one end to their respective ends of the magnet and having their other ends free and arranged in spaced overlying relation to each other, and a pair of rigid members secured to the free ends of said pole pieces and to said pole pieces at a point spaced from the free ends thereof to maintain the spaced relation between such pole pieces.

110

10. A magnetic structure comprising a magnet having a pole piece at each end, said pole pieces being attached at one end to their respective ends of the magnet and having their other ends free and arranged in spaced overlying relation to each other, and a pair of rigid members each secured at one end to the free end of a different one of the pole pieces and each having the other end firmly secured to a portion of the mag-

115

120

125

130

netic structure associated with the pole piece other from that to which the first mentioned end is secured to maintain the spaced relation between said pole pieces.

5 11. In a telephonic apparatus, a magnet, a pair of pole pieces carried by said magnet and arranged in spaced relation to each other, a pair of rigid connecting members adapted to be secured rigidly between said 10 poles to maintain the spaced relation thereof, and means including said members for adjusting the spaced relation between said pole pieces.

12. In telephonic apparatus, a magnet, a 15 pair of pole pieces carried by said magnet and arranged in overlapping spaced relation relative to each other, a pair of rigid L-shaped members extending between and rigidly secured to said pole pieces to rigidly 20 maintain the spaced relation therebetween, an armature movable between said pole pieces, and an armature mounting secured to the inner portions of corresponding legs of the L-shaped members.

25 13. In telephonic apparatus, a magnet, a pair of pole pieces carried by said magnet in overlapping spaced relation, a pair of members extending between and secured to overlapping portions of said pole pieces, 30 and a stationary coil located in the space inclosed between and by said pole pieces and said members, said pole pieces and members providing a housing for said coil and holding it against movement.

35 14. In telephonic apparatus, a magnet, a pair of pole pieces carried by said magnet in overlapping spaced relation, a pair of spaced pole extensions on each of said pole pieces arranged at substantially right angles to 40 said pole pieces, the pole extensions on each pole piece extending toward and arranged in overlapping relation to the extensions of the other pole piece, a pair of members extending between and secured to overlapping 45 portions of each of said pole pieces, said members being arranged at substantially right angles to both said pole pieces and said pole extensions to coöperate therewith to provide a chamber therebetween, and a 50 coil inclosed in said chamber.

55 15. In telephonic apparatus, a magnet, a pair of pole pieces carried by said magnet and arranged in overlapping spaced relation, a pair of members extending between 60 and secured to overlapping portions of each of said pole pieces, an armature, means to mount said armature upon said members for movement between the overlapping portions of said pole pieces, and a stationary coil surrounding said armature located in the space inclosed by and between said pole pieces and members, and held against movement by said pole pieces and members.

65 16. In telephonic apparatus, a magnet, a pair of pole pieces carried by said magnet

and arranged in overlapping spaced relation, a pair of members extending between and secured to overlapping portions of each of said pole pieces to maintain said pole pieces in spaced relation, an armature, and 70 adjustable means to support said armature upon said members for movement between the overlapping portions of said pole pieces and to vary the normal air gap between said armature and pole pieces. 75

17. In telephonic apparatus, a magnet, a pair of pole pieces carried by said magnet and arranged in overlapping adjustable spaced relation, a pair of rigid members extending between and adjustably secured to 80 overlapping portions of each of said pole pieces to maintain the rigid adjusted spaced relation therebetween, an armature supported for movement between the overlapping portions of said pole pieces, and means for 85 adjusting the position of said armature relative to said pole pieces.

18. In telephonic apparatus, a magnet, a pair of pole pieces carried by said magnet and arranged in overlapping adjustable 90 spaced relation, a pair of rigid members extending between and adjustably secured to overlapping portions of each of said pole pieces to maintain the rigid adjusted spaced relation therebetween, an armature supported for movement between the overlapping 95 portions of said pole pieces, and means secured to said members for adjusting the position of said armature relative to said pole pieces independent of the adjustment of the 100 pole pieces relative to each other.

19. In telephonic apparatus, a magnet, a pair of pole pieces carried by said magnet and arranged in overlapping spaced relation, a pair of rigid members extending between and secured to overlapping portions of each of said pole pieces to maintain said pole pieces in spaced relation, an armature, a torsional mounting for said armature secured to said members to position said armature for movement between the overlapping portions of said pole pieces, said torsional mounting normally maintaining said armature in a definite spaced relation relative to 110 said pole pieces. 115

20. In telephonic apparatus, a magnet, a pair of pole pieces carried by said magnet and arranged in overlapping spaced relation, a pair of members extending between and secured to each of said pole pieces, a movable 120 armature, a torsional mounting for said armature secured to said members, a pair of stationary coils surrounding said armature and arranged on opposite sides of said torsional mounting, and means to prevent said 125 coils engaging said mounting.

21. In telephonic apparatus, a magnet, a pair of pole pieces carried thereby and arranged in overlapping spaced relation, a pair of spaced pole extensions on each of 130

said pole pieces, the extensions on each pole piece extending toward and arranged in overlapping relation to the extensions of the other pole piece, a pair of rigid members extending between and secured to overlapping portions of each of said pole pieces, to maintain the spaced relation thereof, an armature

mounted for movement between said pole extensions, and a coil surrounding said armature.

In witness whereof, I hereunto subscribe my name this 29th day of December, A. D. 1917.

10

HENRY C. EGERTON.
